UNITED STATES PATENT OFFICE.

CLARK A. SIGAFOOS, OF OMAHA, NEBRASKA.

FLYING TARGET.

1,227,966.

Specification of Letters Patent. Patented May 29, 1917.

Application filed January 3, 1917. Serial No. 140,397.

To all whom it may concern:

Be it known that I, CLARK A. SIGAFOOS, a citizen of the United States, and a resident of Omaha, in the county of Douglas and State of Nebraska, have invented certain new and useful Improvements in Flying Targets, of which the following is a specification.

My invention relates to flying targets and particularly to targets of the kind commonly designated as "clay pigeons" and extensively used in so-called "trap-shooting". In such use of the targets the same are thrown into the air by well-known trap mechanism which is, or should be, such as to cause rotation of the target during its flight, since the rotation of the target is a very important factor in the breakability thereof when it is struck by scattering shot during flight, and the rotation also contributes to steadiness and uniformity of the flight. The fragility of targets for use in competitive trap-shootings must be gaged very accurately to obtain entirely satisfactory results, and if the targets are too fragile a large percentage thereof will be broken by the trap, while if they are too tough they may be struck by shot during their flight and yet not be broken, resulting in the shooter scoring a miss or failing to be credited with a hit to which he is entitled. In order that targets, of the requisite toughness to withstand throwing without breakage, may be satisfactorily breakable by shot during their flight, it is essential that they be rapidly rotated during the flight, and it has been observed by trap-shooters that targets, which are well-proportioned and satisfactorily breakable when properly thrown, will, when thrown from a defective trap which fails to cause rotation thereof, be much more difficult to break than when they are properly thrown; and such non-rotated targets are frequently known to have been hit by one or more shot without being broken, whereas the identical target if rotating would almost certainly be broken. It appears that the greater breakability of the rotated targets is due to the disruptive tendency of centrifugal forces therein, since in most commercial targets of the described class the greatest thickness and weight of material is in or near the rim thereof, where it has the maximum tendency to disruption by centrifugal force during rotation about a central axis. It is the object of my inven-

tion to provide a target of the described class, having means by which the shooter may instantly determine whether or not the target is properly thrown from the trap and 60 rotating during its flight, and thus to enable the competitive shooter to refuse to fire at an improperly thrown target. A further, and incidental, object of my invention is to provide a target which may be readily seen 65 and distinguished from the various backgrounds against which it may appear when in flight.

In the accompanying drawings, Figure 1 is a perspective view of the target embodying 70 my invention, and Fig. 2 is a plan view of the same.

The target provided by my invention is preferably of the usual dished or saucer-like shape, and may be substantially the 75 same in size, form and material, with any of the common and well-known targets of the described class. The target shown in the drawing has a cylindrical rim 1, a smaller superposed cylindrical portion 2, an inwardly-curving dome-like portion 3 rising from the portion 2 and provided with annular ribs or beads 4, and a flat top 5 having a slightly depressed flat central portion 6. It will be understood (though not shown in 80 the drawing) that the target is hollowed out on its lower side in the usual way, so as to have merely such thickness of material in the walls thereof as to give it the necessary weight and strength to enable it to be 85 thrown from a trap.

The special and distinctive characteristic of my target lies in the provision upon the sides thereof of one or more spots or surface-areas 7 which are painted or otherwise 90 colored differently from the body of the target, so as to contrast therewith. Said contrasting areas 7 are best located upon opposite sides of the target-body, being confined to the surface of the portions, 2, 3 and 100 4, and touching but slightly, if at all, the upper edge of the rim 1, or the marginal portion 5 of the top. The maximum peripheral or circumferential extent of the contrasting areas is preferably about one-fourth of the entire circumference, the form 105 of each spot or contrasting area being roughly elliptical, with the major axis extending circumferentially and the minor axis extending radially of the target-body. 110

As the material from which targets of this class are made is usually black or dark-

colored, the spots or areas 7 will ordinarily be white, or some comparatively light color. It will be understood, however, that should the body of the target be white or light-
5 colored, the spots would be made black or dark-colored, and that the body surface and spots may be of any two colors such that there is a distinct contrast between them. It will be understood further that
10 the coloring may be superficial, as produced by the application of paint or the like to the surface, or that the contrasting colors might be produced by the use of two differently-colored materials for making the target-
15 body, said materials being so molded as to appear upon the proper portions of the surface.

I am well aware that it is a common practice to provide targets of this class with
20 a continuous circumferential band or stripe of a color contrasting with that of the remainder of the surface, the provision of such a band or stripe being for the purpose of enabling the target to be distinctly
25 seen against either light-colored or dark-colored backgrounds. A like effect is produced when my targets are thrown from a properly adjusted trap, so as to have the before-mentioned rotary movement during
30 their flight, since when the target is rapidly rotated the spots or contrasting areas blend together optically to form an apparently-continuous band or stripe extending circumferentially of the target-body, and
35 said stripe or band will appear plainly against the differently-colored rim-portion 1 and top-portions 5 and 6. Should the target be thrown, however, so as not to be properly rotated, the blending of the spots
40 into a continuous-appearing band or stripe will not occur, and the fact that the target has not been properly thrown will at once be obvious to the shooter. In such event a contestant in competitive trap-shooting may
45 refuse to fire at the target and request an adjustment of the trap such as to cause the targets thrown thereby to be properly rotated.

It will be apparent that the location of

the spots or contrasting areas of color should 50 be such that at least a part thereof is visible to the shooter when the target is in any position which it is liable to assume during flight, and that the circumferential extent of the spot or spots should be such that optical blending thereof will occur when the target is rotating at a suitable rate. Both of these requirements are probably best met by the arrangement of the contrasting areas substantially in the manner herein illustrated. 55

Now, having described my invention, what I claim and desire to secure by Letters Patent is:

1. A flying target of fragile material having circumferentially discontinuous surface-portions colored to contrast with the remaining surface-portions thereof. 60

2. In a breakable flying target for trap-shooting, a target-body having surface-areas of contrasting colors each discontinuous circumferentially of a definite portion of the body. 70

3. In a breakable flying target for trap-shooting, a target-body having alternating surface-areas of contrasting colors, said areas being circumferentially discontinuous but adapted to blend optically during rotation of the target-body about a central axis 75 and form an apparently-continuous stripe 80 around said target-body.

4. In a breakable flying target for trap-shooting, a body having a convex surface symmetrical about a central axis, said surface in general being of a uniform color but 85 having portions of contrasting color, said portions being discontinuous circumferentially of the body.

5. In a breakable flying target for trap-shooting, a target-body having uniformly 90 curvilinear surface-elements symmetrical about a central axis, and spots on said surface of a color contrasting with the body-color, said spots adapted to blend optically during rotation of the body about its central axis. 95

C. A. SIGAFOOS.
